Primary Examiner — Selina Sikder(74) *Attorney, Agent, or Firm* — Tarolli, Sundheim, Covell & Tummino LLP(57) **CLAIM**

The ornamental design for a principal battery controller as shown and described.

DESCRIPTION

FIG. 1 is an isometric view of a principal battery controller, showing my new, original, and ornamental design;

FIG. 2 is a top view of the principal battery controller of FIG. 1;

FIG. 3 is a front view of the principal battery controller of FIG. 1;

FIG. 4 is a rear view of the principal battery controller of FIG. 1;

FIG. 5 is a left side view of the principal battery controller of FIG. 1;

FIG. 6 is a right side view of the principal battery controller of FIG. 1; and,

FIG. 7 is a bottom view of the principal battery controller of FIG. 1.

1 Claim, 5 Drawing Sheets(56)
